UNITED STATES PATENT OFFICE.

AARON WOLF AND ANTONI GOVERNAL, OF NEW YORK, N. Y., ASSIGNEES TO METALIC FLEXIBLE HOSE COMPANY, OF BROOKLYN, NEW YORK, A CORPORATION OF NEW JERSEY.

CORNER-POST FASTENING.

1,048,256.

Specification of Letters Patent. Patented Dec. 24, 1912.

Application filed August 2, 1912. Serial No. 712,883.

To all whom it may concern:

Be it known that we, AARON WOLF and ANTONI GOVERNAL, both citizens of the United States, and residents, respectively, of the city of New York, borough of Manhattan, in the county and State of New York, and of the city of New York, borough of Brooklyn, in the county of Kings and State of New York, have invented a new and Improved Corner-Post Fastening, of which the following is a full, clear, and exact description:

This invention relates to certain improvements in corner post fastenings capable of general use in metal structures but more particularly adapted for use in metal bedsteads. It has been proposed to connect the corner post to the side rail of the bedstead by stamped metal parts, by reason of their greater strength and serviceability than the ordinary cast metal parts commonly employed, and the main objects which we seek to accomplish by our invention are to so form these metal parts as to provide a substantially smooth flat joint at the end of the side rail, and to substantially conceal the connecting part carried by the side rail so that the general outward appearance of the corner post fastening will be that of a side rail extending directly to the post and directly connected thereto. Our improved construction may embody certain of the features disclosed in our prior application, Serial No. 703,004, filed June 11, 1912, but the main novel feature of the present construction involves the supporting of the side rail with its outer surfaces substantially flush and smooth with the outer surfaces of the connecting part carried by the post instead of projecting into said connecting part.

Reference is to be had to the accompanying drawings, forming a part of this specification, in which similar characters of reference indicate corresponding parts in all the views, and in which—

Figure 1 is a top plan view of a device constructed in accordance with our invention, the corner post and side rail being shown partly in cross section and partly in dotted lines; Fig. 2 is a perspective view of the two members constituting the fastening and shown in assembled relationship; Fig. 3 is a face view of the post on a somewhat smaller scale and showing one of the members in section; Fig. 4 is a transverse sec-

tion substantially on the line 4—4 of Fig. 1; Fig. 5 is a side elevation of the connecting member adapted to be secured to the side rail; Fig. 6 is an end view of the member shown in Fig. 5, a portion thereof being broken away; Fig. 7 is a plan view of the blank from which the corner post member is formed, and Fig. 8 is a plan view of the blank from which the side rail member is formed.

Our improved corner post fastening in its preferred embodiment, includes two members 10 and 11, the former being adapted to be rigidly secured to a corner post 12, and the latter to a side rail 13. The member 10 is preferably substantially tubular in form and provided with substantially flat, horizontal top and bottom walls 14 and 15, and substantially flat, vertical side walls 16 and 17. The member is formed from a blank, as shown in Fig. 7, and one side wall 16, at its lower edge, is rigidly secured to the bottom wall 15 in any suitable manner, but preferably by two lugs 18 on the edge thereof adapted to extend through apertures 19 in the bottom wall 15. After being extended through these apertures, the lugs may be swaged or riveted over, as indicated in Fig. 4. The tubular member may be secured to the post in any suitable manner but preferably by substantially the same means as is shown in our prior application above referred to. This means includes two extensions 20 at one end of the top and bottom walls which are adapted to be inserted through horizontal slots in the corner posts. These extensions are perforated so that a wedge 21 inside of the post may be driven lengthwise through the perforations and draw the side walls 16 and 17 into rigid engagement with the post. By securing the tubular member 10 in position in this manner, there can be no upward or downward tilting of the outer end of the member and there can be no sidewise movement. In other words, the tubular member and the post would be absolutely rigid in respect to each other.

The other member 11 is preferably formed from a blank substantially as shown in Fig. 8. This blank is adapted to be bent along parallel lines so as to form a tubular portion having top and bottom walls 22 and 23 and side walls 24 and 25 at one end. At the other end, the two walls 22 and 24 extend beyond

the walls 23 and 25, so as to form a right angle portion. The tubular portion of the member 11 is adapted to fit within the tubular portion of the member 10, as shown particularly in Figs. 2 and 4. The parts are so formed that this fit is comparatively close although it is not so snug but what the parts may be readily assembled without the aid of any special tools. The two tubular portions being of the same cross-sectional form, there can be no rotary movement of one in respect to the other, and due to the length of engagement of the tubular portions, there can be no tipping or tilting of the inner member 15 in respect to the outer.

With the tubular portion of the inner member disposed within the tubular portion of the outer member, the right angular extension of the walls 22 and 24 will project beyond the end of the tubular portion of the outer member. These extensions are adapted to be rigidly and permanently secured to the side rail 13 by suitable rivets or in any other approved manner. The side rail comes 25 upon the outside of the member 11, so that the outer surface of one flange of the side rail will come substantially flush with the outer surface of one wall of the member 10 and the outer surface of the other flange of 30 the side rail will lie flush or smooth with the outer surface of another wall of the member 10. Thus the member 11 will be substantially concealed from view as it will have a portion inside of the member 10 and the 35 remaining portion below and behind the side rail. Any suitable means may be employed for detachably but rigidly connecting the two members 10 and 11, but preferably we provide these members with registering 40 apertures 26, through which a circular wedge 27 may be driven. This wedge may serve not only to retain the two members together, but may, at the same time, serve to draw the inner member inwardly to the 45 proper position so that the angle iron may abut against the end of the member 10. This may be easily accomplished by making the openings 26 slightly elliptical.

In the ordinary bedstead construction, it 50 is customary to form the side rail of an angle iron and to position this angle iron so that the vertical flange is on the outer side and the horizontal flange is on the top as illustrated in the form shown, but in some 55 constructions, particularly where slats are employed, it is desired to have the horizontal flange at the lower side so as to form a support for the said slats. It is, of course, evident that the member 11 may be inserted 60 into the member 10, so as to give the angle iron 11 any desired relative position. This may be accomplished by a rotation of the member 11 and by turning the side rail around end for end.

65 For holding the two posts at the head or

at the foot rigid in respect to each other, it is customary to provide a transverse connecting bar which may also be in the form of an angle iron. One important feature of our improved member 10 is that a very 70 simple and convenient means may be provided for said connecting bar. The side wall 16 may have a slot cut therein, as shown in Fig. 7, so as to define a lug 28, which may be bent outwardly as shown in 75 Figs. 1, 2 and 4. This lug may be perforated to facilitate the riveting or bolting of a transverse connecting bar 29 thereto. By forming the bottom wall 15 slightly wider than the top wall, there is left an outwardly- 80 extending flange which serves not only to permit the proper placing of the openings 19 but also serves as a base flange upon which a portion of the lug 28 rests and thus 85 additionally supports the latter. By forming the lug 28 as shown, the side wall 16 may be rigidly connected to the bottom wall at each side of the lug and the strain on the lug prevented from opening up the outer tubular member.

Our improved construction involving only two main parts, which are easily and cheaply formed from stamped metal, is very economical to manufacture and when formed of the proper grade of steel, is far stronger and less fragile than cast metal parts. The fastening may be readily assembled and disassembled without the aid of any special tools. During shipment and storage, the two tubular members of the head may be easily and 90 readily connected to the two tubular members of the foot, by short pieces of angle iron or metal tubes perforated at their ends and inserted in said tubular members. The wedges 27 may be employed for holding 95 these short connecting pieces in place, and thus the liability of loss or misplacement of the wedge is reduced to a minimum.

Having thus described our invention, we claim as new and desire to secure by Let- 100 ters Patent:

1. In combination, a corner post, a horizontally-disposed tubular member secured thereto, a side rail in the form of an angle iron abutting against the end of said member and in alinement therewith, and a supporting member secured to said side rail and 115 slidably into said tubular member upon an endwise movement of said side rail.

2. In combination, a corner post, a horizontally-disposed tubular member secured thereto, a side rail in the form of an angle iron abutting against the end of said member and in alinement therewith, a supporting member secured to said side rail and 120 projecting endwise into said tubular member, and a detachable retaining device for normally preventing the removal of said supporting member.

3. In combination, a corner post, a hori- 130

zontally-disposed tubular member secured thereto, a side rail in the form of an angle iron abutting against the end of said member and in alinement therewith, a supporting member secured to said side rail and projecting endwise into said tubular member, and a wedge projecting through said tubular member and said supporting member for normally preventing their disengagement.

4. In combination, a corner post, a horizontally-disposed tubular member secured thereto, a side rail in alinement therewith, a supporting member secured to said side rail and slideable into said tubular member upon an endwise movement of said side rail, and a separable wedge for preventing their separation.

5. In combination, a corner post, a substantially horizontal tubular member secured thereto, a side rail in the form of an angle iron having its upper surface substantially flush with the upper surface of said member, and means supported within said member for retaining said side rail in position.

6. In combination, a corner post, a horizontally-disposed tubular member secured thereto, a side rail in alinement therewith, and a supporting member having a tubular portion projecting into said tubular member and an angular portion rigidly secured to said side rail.

7. In combination, a corner post, a horizontally-disposed tubular member secured thereto, a side rail in alinement therewith, and a supporting member having a tubular portion projecting into said tubular member and a portion rigidly secured to said side rail.

8. In combination, a corner post, a side rail, and means connecting said side rail to said corner post, including a member rigidly secured to said post and having an open end, a supporting member rigidly secured to said side rail and projecting into said first mentioned member, and a vertically-disposed wedge extending through the upper portion of said tubular member and into

said supporting member and normally preventing the withdrawal of said supporting member.

9. In combination, a corner post, a side rail, a supporting member secured to said side rail and formed from a sheet metal blank, one end of said member being substantially angular in cross-section and the opposite end of said member being substantially tubular and projecting beyond the end of said side rail, and means carried by said post for engaging with and supporting said tubular portion.

10. A corner post fastening, including two members formed of sheet metal bent to substantially tubular form and adapted to telescope with one tubular portion within the other, means for securing one of said members to a corner post, and means for securing the other of said members to a side rail.

11. In combination, a corner post, a horizontally-disposed tubular member secured thereto, a side rail having a tubular member secured thereto, one of said tubular members being adapted to telescope with the other upon a longitudinal movement of the side rail in respect to the corner post, and a pin extending transversely through both tubular members to prevent their separation.

12. In combination, a corner post, a horizontally-disposed member secured thereto and having a portion substantially rectangular in cross section, a side rail in the form of an angle iron abutting against the end of said member, and a supporting member secured to said side rail and having a projecting portion substantially rectangular in cross section, and normally disposed inside of the other rectangular portion.

Signed at New York city in the county of New York and State of New York, this 23rd day of July, A. D. 1912.
